(57) **CLAIM**

The ornamental design for a storage apparatus as shown and described.

DESCRIPTION

FIG. 1 is a perspective view of a storage apparatus, according to the present invention;

FIG. 2 is a front elevational view of the storage apparatus of FIG. 1;

FIG. 3 is a rear elevational view of the storage apparatus of FIG. 1;

FIG. 4 is a right side elevational view of the storage apparatus of FIG. 1;

FIG. 5 is a left side elevational view of the storage apparatus of FIG. 1;

FIG. 6 is a top plan view of the storage apparatus of FIG. 1; and,

FIG. 7 is a bottom plan view of the storage apparatus of FIG. 1.

1 Claim, 5 Drawing Sheets
